UNITED STATES PATENT OFFICE

JOSEPH ZUBATY, OF FLINT, MICHIGAN, ASSIGNOR TO A C SPARK PLUG COMPANY, OF FLINT, MICHIGAN, A COMPANY OF MICHIGAN

ODOMETER

Application filed March 11, 1926. Serial No. 84,097.

This invention relates to a novel speedometer having combined therewith an odometer as usual.

The new instrument has been designed to overcome various objections and limitations inherent in prior devices, and to this end involves a single frame element which is somewhat of box shape to permit easy die casting and in which the odometer shaft, the rotor shaft, and the interconnecting gearing are directly mounted. This is an improvement over a frame of detachable parts in that it simplifies manufacture and secures proper alignment of parts.

This particular application relates to features of novelty in the odometer used in the combination. The novel features have been designed with the view to make an improved odometer for use with an associated speedometer on vehicles, but it will be understood that the construction may be useful in other relations.

Among the objects which the invention seeks to accomplish are the following: An improvement in the odometer drive including means for assembling and securing in position the several shafts; an improved position of the reset stem; an improved reset mechanism; and an improved relation between the odometer figure wheels and their related star wheels.

The above mentioned and other objects are obtained by the structure herein described and shown on the accompanying drawing. It will be understood that this structure is illustrative of what is now believed to be the best to accomplish the above objects but that changes and modifications may be made within the scope of the claims.

In the drawing:

Figure 1 is a front view of the combined speedometer and odometer on an enlarged scale, the face plate being removed. Figure 2 is a side elevation looking from the left of Figure 1. Figure 3 is a vertical sectional view of the trip wheel set of the odometer and its reset mechanism. Figure 4 is a side elevation, parts being in section, looking from the right of Figure 1. Figure 5 is a section on line 5-5 of Figure 3. Figure 6

is a vertical sectional view illustrating the assembly of the second worm shaft. Figure 7 is a perspective view of a detail.

Referring now to the drawing for a complete description, numeral 1 represents a frame which carries the speedometer and odometer parts. This frame is a single box shaped member and receives the various parts of the speedometer and odometer, thereby simplifying the manufacture and ensuring a correct alignment of parts. 3 is a mounting plate, annular in shape, and secured to the frame by fastening means 5. This frame is to be enclosed in a casing 6. For connecting the casing 6 to the mounting plate 3 there is shown a face plate 8, a glass 10 and a bezel 12. From Figure 2 it will be understood that the bezel engages the front of the glass and is bent over and holds together a flange on the casing, the mounting plate and also the face plate. It may be said here that the mounting plate 3 possesses some degree of resiliency whereby shocks given to the casing 6 are avoided by the frame and its speedometer and odometer mechanism.

The drive shaft for the speedometer is admitted to the frame at 7 where it is coupled to a vertical rotor shaft, not shown. This rotor shaft extends through the vertical frame portion illustrated in Figure 2 and Figure 4. This shaft, as usual, carries a rotor (not shown as it is not material to this invention). The speed cup which surrounds the rotor appears as at 9, its spindle being designated as 11 and the controlling spring by 13. The pin 15 and lug 17 constitute the zero stop mechanism. It will be observed that the upper spindle bearing is carried by frame member 19 secured by screws 21 to the frame member.

Extending at right angles to the rotor shaft and geared thereto at 23 at a point just beneath the rotor and speed cup is the so-called second worm shaft 25. This shaft is arranged to be assembled from either end of the frame as at 27 and 29 (see Figure 1 and Figure 6). For holding this shaft from axial movement, a U shaped clip is used, as shown at 31. This clip enters a recess 30 in

the frame and engages a groove 34 in the shaft. It has a V shaped portion 32 engaging a depression in the frame member.

Adjacent one end of this second worm shaft 5 it is formed with a worm 33. A third worm shaft 35 extends vertically (it being understood that the speedometer is mounted on the dash). This shaft is mounted at two spaced positions, 37 and 39 in the frame member as 10 shown in Figure 4. It overlies the second worm shaft and has a worm 41 for driving engagement therewith. A clip 43 of U shape has its bend and one leg engaged over a frame part and its long leg 45 is forked to 15 engage a grooved part of the shaft 35 to hold this shaft in its vertical position and prevent axial movement. This structure is shown at Figure 1 and Figure 4. It will be noticed also from an inspection of Figure 1 that 20 when the casing is in position over the frame, the clip lies so closely adjacent to the casing that it cannot slip off and release its hold on shaft 35. This third worm shaft is provided near its lower end with a worm 47 which is in 25 driving engagement with a worm gear 49. This worm gear 49 is on the shaft 50 of the "season" set of figure wheels of the odometer. The worm 49 is made use of to drive the "trip" set of figure wheels. To that end it engages 30 an idler 51 which in turn drives a spur gear 53. This spur gear, by a mechanism to be described, drives the "trip" set wheels.

A disk 55 on shaft 50 has two teeth to engage a tooth of a star wheel 57 on star wheel 35 shaft 59. This star wheel is in driving engagement with the figure wheel 61 of lowest denomination of the "season" set. In a similar way each succeeding wheel of the season set is driven, and the "units" wheels 63 and 40 the "tens" wheels 65 of the "trip" set are driven from the fractional wheel 67, there being, as will be understood, a second star wheel shaft as shown in Figure 1. A feature to 45 which I attribute considerable importance in this connection is the relative position of the shafts of the figure wheels and the shafts of their respective star wheels. The star wheel shafts have commonly been placed closely adjacent each other and between the 50 two figure wheel shafts. By locating the star wheel shafts each in the same relation to its figure wheel shafts, as for example, forward and below, as best shown in Figure 2, the double tooth driving member of each figure 55 wheel may be placed in the same position on its wheel whether the wheel be intended for the "season" set or the "trip" set. It will be seen from Figure 1 that this double tooth may be between Figures 1 and 2 on each wheel of 60 both sets. No "rights" or "lefts" are therefore required and the figure wheels become interchangeable, thus doing away with the necessity of manufacturing the double set of figure wheels and consequently effecting considerable economy.

In connection with the mounting of the shafts of the figure wheels and star wheels another improvement is to be noted. These shafts engage at their ends in bearing portions of the frame and to secure them in position in a manner to prevent axial movement, two clips 69 are employed, one for each pair of shafts. These clips are alike and each is formed as a U shaped stamping having a short arm 71 engaging an inner frame wall and an outer arm of approximately L shape. A suitably shaped notch in each end of the L shaped arm engages a groove adjacent the end of the number wheel shaft and its adjacent star wheel shaft. This structure 75 is clearly shown in the perspective view, Figure 7, also in Figure 1 and Figure 2. The end of the shorter arm may be bent up slightly to facilitate assembly. When placed in position its frictional grip on the frame holds 80 it in position such that the shafts are prevented from longitudinal displacement. It will be observed from an inspection of Figure 2 that the bent portion of this clip lies closely beneath the face plate when that plate is assembled on the casing. Because of this relative position of the clip and the face plate 85 it is impossible for the clip to slip forward and release the shafts which it holds.

Figure 3 shows to best advantage the reset 90 mechanism. Here will be seen a sleeve 73 rotatably and slidably mounted upon the trip figure wheel shaft 75. At one end this sleeve carries the spur gear 53 mentioned above engaging the idler 51. The other end of the 95 sleeve is non-circular in shape as at 79 and is slidably within a correspondingly shaped opening 81 in the fractional wheel 67. In its various positions of movement the sleeve is always in driving engagement with the fractional wheel, but if moved deep into the opening of the figure wheel the gear 53 becomes 100 disengaged from gear 51. For the purpose of normally maintaining the gear engagement a spiral coil spring 82 is used. This spring engages the surface of the fractional wheel and an abutment 83 on the sleeve, which takes the form of a conical cam. The sleeve 73, gear 53 and the conical cam of the abutment 83 together form what I call a cam and gear element, and the conical cam is engaged by a corresponding cam 87 on the reset shaft 89. Just beneath the cam 87 on the shaft 89 is a gear 91. The reset shaft is mounted to be rotated and reciprocated in a frame extension 92. As this 105 reset shaft is projected inwardly the cam members engage and the gear 53 is disengaged from the idler 51 and the gear element 91 on the reset spindle is brought into engagement with the pinion 53. Rotation of the reset spindle under these circumstances causes the rotation of the cam member and enables the trip set to be given a desired reading.

Another feature of importance should be observed in connection with this reset device. 110

The angle at which the reset spindle is positioned will be seen from an inspection of Figure 1 and Figure 2 to be about 15° from the vertical in two directions, laterally and rearwardly. This position of the reset spindle secures the following advantageous results. It facilitates the mounting of the instrument from the front through an opening provided therefor in the instrument board. It gives sufficient distance between the driving flexible shaft and the handle portion of the reset spindle so that the driver's fingers are not likely to touch the flexible drive shaft. It provides also in a similar way sufficient distance between the lower edge of the instrument board and the spindle to give room for convenient manipulation. Furthermore this position makes possible a very desirable pitch to the cam members for operating the slideable clutch.

I claim:

1. A reset mechanism for figure wheels or the like comprising a shaft, a wheel thereon, driving means therefor, means slideable on the shaft in constant driving engagement with the wheel and having a gear movable into and out of driving relation with the driving means, means for moving said slideable means including a reset spindle having a gear element thereon engaging, when in one position, the gear of the slideable means.

2. A reset device comprising a shaft, a figure wheel thereon, driving means, a cam and gear element slideable on said shaft, the cam and gear element being in constant driving engagement with the figure wheel, and its gear normally in driving engagement with said driving means, a reset spindle having a cam and a gear, the cam cooperating with the cam of the slideable cam and gear element to release the drive and the gear cooperating with the gear of the cam and gear element for the purpose of resetting.

3. In reset mechanism of the class described, a shaft; a wheel carried by and rotatable about the axis of said shaft; a gear rotatable about and movable along the same axis as that about which said wheel is rotatable, and which gear is in constant driving engagement with said wheel so as to always drive the same; a driving gear with which said first mentioned gear is normally in mesh; a reciprocating and rotatable reset member having a gear which is normally out of mesh with said first mentioned gear; and cooperating members associated with said first mentioned gear and with said reset member for moving said gear along the axis aforesaid and out of mesh with said driving gear, and for simultaneously causing the gear upon said reset member and said first mentioned gear to come into mesh with one another.

In testimony whereof I affix my signature.
